(57) CLAIM

The ornamental design for a label portion of a fabric and air freshener package, as shown and described.

DESCRIPTION

The FIGURE is a front elevation view of a label portion of a fabric and air freshener package showing our new design.

The evenly dashed broken lines in the drawings illustrate the portions of the design that form no part of the claim. The dot-dot-dash broken lines in the drawings define the bounds of the claim and form no part thereof.
